KNIFE SHARPENING DEVICE

Filed Feb. 24, 1931

INVENTOR:
GEORGE A. ZAHLER
BY William J. Gerrold,
ATTORNEY

UNITED STATES PATENT OFFICE

GEORGE A. ZAHLER, OF CLEVELAND, OHIO

KNIFE SHARPENING DEVICE

Application filed February 24, 1931. Serial No. 517,905.

This invention, as indicated, relates to a knife sharpening device. More particularly, it comprises a device for cutting a knife edge to a degree of sharpness with file surfaces of special characteristics and position and then finishing such edge with finishing surfaces positionally disposed upon said device with reference to said special file surfaces.

Heretofore in sharpening knives it has been the general practice to rely on what is termed a sharpening "steel", in the form of a tapered bar having cutting grooves etched longitudinally upon its surface, and having a handle at its heavier end, but a true sharpening operation on the knife usually has been carried out as a separate operation on a grinding wheel or with a stone or file, and a finishing effect has been given the edge as a separate subsequent operation.

The present invention has for its principal object the providing of a hand implement which will combine positionally and functionally related means for sharpening and finishing a knife edge. The implement, as a further object, has in view the formation upon opposite sides of an elongated tapered bar of hardened steel or like suitable material, of surfaces having a cutting effect when stroked alternately by the knife edge in a predetermined direction on opposite sides of the implement. It also includes the further object of providing an implement which is formed at the intermediate points about its circumferential extent with finishing surfaces such as are usually provided on a sharpening steel by the etched longitudinal lines thereon.

Another object of the invention is to provide an article of the character just described which has its sharpening and finishing surfaces definitely spaced from each other so as to prevent interference and accidental use of two operatively different surfaces at the same time.

Another object of the invention is to provide means on the implement to assist the user in positioning the implement for sharpening action when stroked in a right handed or left handed manner, according to the particular dexterity of the user, and also with

means to assist the user in positioning the finishing surfaces.

Another object of the invention is to provide grooves intermediate the sharpening and finishing surfaces which will not only space said surfaces for independent non-interfering use of each such surface, but will also receive chips which might otherwise remain in the recesses of the cutting or finishing surfaces.

Other and further objects of the invention will appear in the course of the following description. To the accomplishment of the foregoing and related ends, said invention, then, consists of the means hereinafter fully described and particularly pointed out in the claims.

The annexed drawing and the following description set forth certain structures embodying the invention, such disclosed means constituting, however, but several of various structural forms in which the principle of the invention may be used.

In said annexed drawing:

Figure 1 is a front elevation of an implement for use in large establishments, embodying the principles of my invention, showing a sharpening surface and positioning thumb rest toward the observer, with the guard member shown partially in section;

Figure 2 is a side elevation of the device shown in Figure 1, showing a finishing surface toward the observer;

Figure 3 is a rear elevation of the device shown in Figure 1 with the companion sharpening surface toward the observer;

Figure 4 is an enlarged sectional view taken along the line 4-4 shown in Figure 1, looking in the direction of the arrows;

Figure 5 is a view, partially in section, taken along the line 5-5 shown in Figure 1;

Figure 6 is a greatly enlarged longitudinal sectional view taken between the lines 6-6 shown in Figure 2;

Figures 7, 8 and 9 are views similar to those shown respectively in Figures 1, 2 and 3, but illustrating an implement primarily for household use;

Figure 10 is an enlarged sectional view

taken along the line 10—10 shown in Figure 7, looking in the direction of the arrows;

Figure 11 is a greatly enlarged longitudinal sectional view taken between the lines 11—11, shown in Figure 8; and

5 Figure 12 is a diagrammatic sectional view showing a modified form of structure.

As is clearly shown in the drawing, the device embodying the features of the invention has the general appearance of a standard 10 knife sharpening "steel", such as is used in kitchens of large establishments as well as in the household. It should be pointed out, however, that ordinary sharpening steels are not limited to use in any particular position or required to be stroked toward or away 15 from the handle. They are "universal" as to position and direction of use. In this way these devices as well as all devices of the prior art differ from the present invention.

20 The device herein set forth is not adapted for universal positioning or direction of use. It has a single predetermined position with reference to the sharpening action but may be 25 considered of universal positioning with reference to the finishing action although convenience of handling would make it desirable also to use the finishing surfaces in a predetermined position with relation to the adjacent 30 sharpening surfaces.

The implements for household use are preferably designed to be used by stroking the knife from the handle toward the point of the implement, whereas implements for use 35 by butchers and chefs in larger establishments are preferably designed to be stroked from the point of the implement toward the handle, as this conforms to well established customs of the users.

40 It will be noted from Figures 1, 2, 3, 7, 8 and 9, that the implement comprises a body portion tapered after the manner of the usual sharpening steel and formed on opposite sides with file surfaces angularly cut so as to have 45 parallel rows of teeth extending in the same direction on said opposite sides. The general structure of the device is shown in Figs. 1, 2, 3, 7, 8 and 9, the first three views illustrating the larger implement designed for use 50 in larger establishments such as hotels restaurants, and shops for the handling of meats and the like, and the last mentioned views illustrating the implement designed for household use. In each of said implements 55 there is provided a body portion 1 formed preferably of steel suitably treated to have the necessary qualities for the sharpening and finishing of knife edges. The body portion is tapered toward the free end having a slightly 60 curved surface increasing in degree of curvature toward the free end after the manner of the standard sharpening steel. The extreme end 2 of the body portion as well as the portion 3 adjacent the point of attachment of 65 the handle are finished as a smooth surface.

The handle 4 is preferably formed of wood and is standard form and may be provided with a terminal member 5 suitably apertured to receive a ring 6. The handle is preferably shaped to conveniently fit the hand of the user and adjacent its lower end is formed with a thumb rest 7. The thumb rest 7 is slightly offset from the central axial line of one of the sharpening surfaces as will be hereinafter explained. At a point opposite the position of the thumb rest a button 8 is provided to serve as a positioning means for a party using the device in the left hand rather than in the right hand. Between the position of the button and the position of the thumb rest small-headed studs 9—10 are provided to assist the user in positioning the finishing surfaces.

At the meeting point of the handle with the body portion a guard 11 is provided, said guard as shown in Figures 1 to 7 having a disc-like extension over which is engaged a protecting disc 12 preferably formed of aluminum, the edges of which are spun over the edges of the guard 11. By making this disc facing the steel of aluminum or like soft metal, any accidental bringing of the sharpened edge against the guard will not permanently injure the edge as the metal is soft enough to prevent the breakage of the edge 95 of the blade of the knife being sharpened.

As will more clearly appear from Figures 4 and 5 of the drawing, the body portion of the implement is formed with four operative surfaces, two of said surfaces 13—14 being file surfaces and two of said surfaces 15—16 being finishing surfaces, and each of said surfaces being separated from the adjacent surfaces by a longitudinal groove 17. The groove may take the form of a U-shaped groove, as is shown more particularly in Figures 4 and 5, or may take the form of a V-shaped groove 18, as is shown more particularly in Figure 10. The sharpening surfaces 13—14 are preferably file surfaces with the cutting edges formed with parallel rows of teeth extending from left to right, as is more particularly shown in Figure 1. The teeth on opposite sides of the implement each extend in the same angular direction, being parallel to each other, although when the implement is reversed, the direction of the teeth on the reverse side 14 would be from right to left as in an upward direction, as is clearly shown in the drawing. In the space marked 6—6 in Figure 2, the parallelism of the cutting teeth of the surfaces 13—14 is clearly illustrated.

The inclination of the cutting teeth is opposite to the direction in which the knife is to be stroked upon the sharpening implement, thus in the implement designed for use in larger establishments, as shown in Figures 1 to 6, the teeth 19 of the file surface are inclined toward the free end of the implement

so that cutting action takes place as the knife edge is moved in a direction toward the handle. In the form of implement intended for household use, the teeth 20 of the file surfaces are angularly directed toward the handle portion of the implement so that as the knife blade is stroked over the sharpening surfaces in a direction toward the free end of the implement suitable cutting action will take place.

In each instance the intermediate surfaces 15-16 are provided with shallow longitudinal grooves providing what is known as "etched" surfaces.

18 The difference in the positioning of the file surfaces is clearly brought out in Figures 7 to 9, as compared with Figures 1 to 3. As has been stated, the grooves of the file surface extend from left to right in an upward direction in Figure 1, and from right to left in an upward direction in Figure 7, the grooves being preferably at an angle of about 20° to the horizontal. They extend parallel to each other as is shown in the space marked 25 11-11 in Figure 8 and preferably on the reverse side of the implement, as is shown in Figure 9, the grooves of the cutting surface extend from left to right in an upward direction instead of from right to left in an upward direction as shown in Figure 3.

The grooves 17 and 18 or any other configuration of groove which may be found desirable not only serve to space the surfaces so that a knife blade applied to the intermediate surfaces will not accidentally contact with an adjacent surface having another operative effect upon the knife edge, but also serve as a means for receiving the chips which accumulate in the teeth of the file surfaces 40 or the longitudinal etchings of the finishing surfaces. It will be noted that the edges of the surfaces adjacent the grooves are rounded so as to prevent any cutting action upon the knife edge by the extreme edges of either type 45 of surfaces.

The form of construction illustrated in Figure 12 provides for the application of the knife edge to each of the sharpening surfaces at a central point of such surfaces which 50 is slightly in advance of a vertical plane extended through the implement. This is accomplished by forming the finishing surface 21 at the front of the implement of lesser extent circumferentially of the body than the 55 rearward finishing surface 22. Thus the grooves 23-24 will be closer to each other than the true 90° position, while the grooves 25-26 will be spaced from each other more than a distance of 90° on the circumference 60 of the body of the implement. The knife edge accordingly, when stroked upon the cutting surface, will be brought against the center of the cutting edge at a point 28 on one side and at a point 29 on the opposite side 65 with the knife edge exactly tangential to the

center of each of said surfaces from a common point of movement in front of said implement.

The manner of using the implement has already been indicated in connection with the description of its construction. The implement obviously may be held in various positions but the usual method of sharpening a knife is carried out by holding the implement in the left hand with the thumb on the thumb rest and with the point of the implement extending at a sharp upward angle. The knife to be sharpened is then held in the right hand and when the larger implement shown in Figures 1 to 3 is used, the knife is stroked downwardly across the cutting surfaces alternately until the desired sharpness of edge is obtained and thereafter the implement is rotated through an angle of 90° in either direction and the knife edge again is preferably stroked downwardly alternately on the opposite sides of the finishing surfaces until the desired finish of the edge is produced.

When the household type of implement is used, the implement is held at a slight angle to the horizontal and the knife is stroked alternately on the opposite edges of the sharpening surfaces toward the point of the implement until the desired cutting edge is produced and the implement is then rotated through an angle of 90° and the knife is then stroked preferably toward the point of the implement until the desired finish to the edge of the same is produced.

Thus it will be noted that the implement must in each instance be held at a particular position and stroked in a particular direction in order to produce the sharpening or cutting effect upon the edge of the blade of the knife. The finishing effect may be produced by stroking the knife differently or from either side but it is quite obvious that a person using the device in a certain manner for the sharpening operation will use substantially the same stroke upon the other surface for the finishing operation.

When the device is to be used by a left handed person the implement obviously is held in the right hand with the thumb of the user upon the button 8 instead of on the thumb rest 7, all of the other operations being substantially the same, the knife being stroked against the body of the implement by the use of the operator's left hand and the direction of stroke, the same being toward the handle portion in case of the device shown in Figures 1 to 3, and toward the free end of the device in case of a household implement such as is shown in Figures 7 to 9.

Other modes of applying the principle of my invention may be employed instead of the one explained, change being made as regards the structure herein disclosed, provided the means stated by any of the following claims

or the equivalent of such stated means be employed.

I therefore particularly point out and distinctly claim as my invention:

5 1. A knife sharpening device having in combination an elongated body member substantially circular in cross-section presenting a plurality of spaced transversely curved operative surfaces, two of said operative surfaces having rows of file teeth inclined in one direction only, and the teeth of said two operative surfaces being parallel to each other, and being disposed substantially opposite each other and being uni-directional in use, said surfaces having a preliminary cutting effect, and two other of said operative surfaces disposed substantially opposite each other and intermediate said first-named two surfaces, said intermediate surfaces having a structure to produce a finishing effect.

10 2. A knife sharpening device having in combination an elongated body member substantially circular in cross-section presenting a plurality of radially spaced transversely curved longitudinally extending operative surfaces, two of said operative surfaces having rows of file teeth inclined in one direction only, and the teeth of said two operative surfaces being parallel to each other, and being disposed substantially opposite each other and being uni-directional in use and each of said surfaces being spaced for independent use to its extreme margins from any adjacent operative surfaces by means of longitudinally extending grooves with rounded edges.

15 3. A knife sharpening device having in combination an elongated body member presenting a plurality of radially spaced longitudinally extending operative surfaces, two of said operative surfaces having rows of file teeth inclined in one direction only, and the teeth of said two operative surfaces being parallel to each other, and being disposed substantially opposite each other and being uni-directional in use and comprising segments of a substantially cylindrical surface, the central longitudinal axial lines of each of said two operative surfaces being spaced circumferentially a distance of less than 180° on 20 the side toward the position of the article to be operated upon, and a distinctive thumb contact element for determining the single position for using said sharpening surfaces.

25 4. A knife sharpening device having in combination an elongated body member presenting a plurality of radially spaced longitudinally extending operative surfaces, two of said operative surfaces having rows of file teeth inclined in one direction only, and the teeth of said two operative surfaces being parallel to each other, and being disposed substantially opposite each other and being uni-directional in use and comprising segments of a substantially cylindrical surface, the central longitudinal axial lines of each of

30 said two operative surfaces being spaced circumferentially a distance of less than 180° on the side toward the position of the article to be operated upon sufficient to bring said article to be sharpened tangentially against the central portions of each of said uni-directional operative surfaces from a single relatively fixed point of support for said article to be sharpened.

Signed by me this 9th day of February, 75
1931.

GEORGE A. ZAHLER.
